H. F. WAITE,
X-RAY TUBE HOLDER AND SHIELD,
APPLICATION FILED SEPT. 20, 1917.

Patented June 24, 1919.

22 23 20 Inventor
23 Harry J. Waite
24, his Attorney
O. Elvyn Edwards, Jr.

UNITED STATES PATENT OFFICE.

HARRY F. WAITE, OF NEW YORK, N. Y.

X-RAY-TUBE HOLDER AND SHIELD.

1,307,385.

Specification of Letters Patent. Patented June 24, 1919.

Application filed September 20, 1917. Serial No. 192,251.

To all whom it may concern:

Be it known that I, HARRY F. WAITE, a citizen of the United States, and a resident of the city of New York, county of Queens, 5 and State of New York, have invented a new and useful Improvement in X-Ray-Tube Holders and Shields, of which the following is a specification.

The object of my invention is to provide a device of this class, which may be used to hold a tube and protect both the patient and the person operating the apparatus and at the same time to provide a good, durable and adjustable apparatus which will be reliable 5 in its operation, and discharge properly all the functions for which it is designed. This and other objects are accomplished by my invention, one embodiment of which is hereinafter more particularly set forth.

For a more particular description of my invention, reference is to be had to the accompanying drawing, forming a part hereof, in which,

Figure 1 is a plan view of my shield and holder,

Fig. 2 is an enlarged end elevation of the shield and a portion of the holder.

Fig. 3 is a partial sectional view taken substantially on the line 3—3 of Fig. 2 looking in the direction of the arrows.

Throughout the various views of the drawing similar reference characters designate similar parts.

My invention contains an improved holder 5 1 which is provided with a shield 2 which is mounted in a suitable clamp 3 which in turn is secured by a pivotal connection 4 with a pivoted arm 5 which is connected by a pivotal connection 6 to a second pivotal arm 7 which in turn is also mounted to slide radially or turn in a hub 8 and be held at any desired position by set screw 9 and this hub 8 is pivotally mounted in a bracket 10 which is fixed and provided with an adjusting screw mechanism 11 and a set screw 12, so that when the screw 12 is set, the mechanism 11 may be operated to shift the hub about its axis and when the desired position is secured, the hub 8 may be left in this position. 5 or if the hub 8 is considerably removed from its correct position, the set screw 12 may be released and the hub 8 then turned without regard to the adjusting screw 11 until approximately in its correct position, and then 5 this screw 12 may be tightened and the adjusting screw 11 used for delicate adjusting.

More particularly, the shield 2 is preferably made substantially in the shape shown, that is, with two parts, 13 and 14, which are connected with a ground glass joint 15 except at the hole 16 where an opening is had for a neck of an X-ray tube. The part 14 has a laterally extending tubular projection 17 which allows direct access to the X-ray tube, and through which X-rays are projected when the apparatus is in use, and the part 13 has a corresponding tubular projection 18 which is preferably placed in axial alinement with the tubular projection 17 and runs in the opposite direction and is made 70 smaller in diameter but longer in length so as to receive and hold a neck of an X-ray tube.

The clamp 3 is provided with a cushion collar 19 which is adapted to embrace the 75 neck 17 and hold the same where it joins the bulb of the part 14 and the cushion ring 19 is provided with laterally extending spring extensions 20 which run nearly parallel with the globe 14 and end in laterally extending perforated ears 21 which receive cap screws 22 and are pressed by their nuts 23. The screws 22 also pass through corresponding ears 24 which extend from spring arms 25 that engage a perforated plate 26 which 85 is preferably made of wood or similar material, and embraces the neck 18 adjacent to where it leaves the bulb of the part 13. The tension on the parts 20 and 25, caused by the pressure exerted by means of the screws 22, 90 causes the ring 19 and plate 26 to force the parts 13 and 14 into intimate contact in a manner which holds an X-ray tube securely at all times and in any desired position. The structure by which the plate 26 is secured 95 will now be set forth. A laterally extending bulb 27 is fixed to the plate 26 in any suitable manner and passing therethrough is a screw 28 which has a spring 29 pressing against washers 30 so as to keep the projection 27 from turning freely on the screw 28, so that the projection 27 and the part carried thereby may be adjusted on the screw 28 in any desired position. The screw 28 is fixed in place in the pivoted arm 5 by 100 means of a lock nut 31 which is placed therein in any convenient location so that under no circumstances will the screw 28 turn when the lock nut 31 is fixed to the screw. The other end of the arm 5 is pivoted at 6 in a clevis or in any other suitable manner and the arm 7 is mounted to slide

radially in the hub 8 and as it is circular in cross section, it can not only slide therein, but may also turn therein when the set screw 9 is released. The adjusting screw 11 and its connections may be made in any suitable way as by having a nut 32 on the screw 11 connected to the bracket 10 and one end of the screw 11 has a ball and socket connection with the extended end of an arm 33 which may be secured to the hub 8 through the set screw 12 or in any other suitable way.

In view of the foregoing, the use of my improved holder and shield will be readily understood. Once the patient is in a position to have the apparatus used, as a patient in a dentist's chair, the apparatus is placed and adjusted until the X-rays may be projected exactly at the desired parts, and then the exposure is had in the conventional way. Meanwhile the operator is entirely protected while operating the apparatus, and the patient is protected everywhere except where the X-rays are projected to obtain the desired results.

While I have shown and described one embodiment of my invention, it is obvious that it is not restricted thereto but is broad enough to come within the scope of the annexed claims.

Having thus described my invention, what I claim is:

1. In a device of the class described, a two part protector adapted to hold an X-ray tube and provided with two necks, a clamp 35 for holding the two parts in fixed relation while containing a tube so that X-rays may be projected through one of the necks and means for permitting the clamp to be held and adjusted in any desired position while holding the tube.

2. In a device of the class described, an X-ray tube shield in two parts connected by a joint having a recess in each part which register to form a neck hole and a neck extending from each part and a clamp for holding the said parts in fixed relation so that X-rays may be projected through one of the necks.

HARRY F. WAITE.
